(57) **CLAIM**

The ornamental design for an electrode device, as shown and described.

DESCRIPTION

FIG. 1 is a front elevational view of the electrode device with a locking pin and electrode cap present;

FIG. 2 is a rear elevational view of the device of FIG. 1; FIG. 3 is a top plan view of the device of FIG. 1;

FIG. 4 is a bottom plan view of the device of FIG. 1; FIG. 5 is a side elevational view of the device of FIG. 1;

FIG. 6 is a perspective view of the device of FIG. 1; FIG. 7 is a top plan view of the electrode device with the electrode deployed;

FIG. 8 is a perspective view of the device of FIG. 7;

FIG. 9 is a front elevation view of the device of FIG. 7;

FIG. 10 is a rear elevational view of the device of FIG. 7; FIG. 11 is a side elevational view of the device of FIG. 7; and,

FIG. 12 is a bottom plan view of the device of FIG. 7.
